Pierre J. Barnes
ATTORNEY

UNITED STATES PATENT OFFICE.

WILLIAM S. HARRIS, OF BREMERTON, WASHINGTON.

AUTOMOBILE-SIGNAL.

1,362,531.

Specification of Letters Patent. Patented Dec. 14, 1920.

Application filed March 29, 1920. Serial No. 369,573.

To all whom it may concern:

Be it known that I, WILLIAM S. HARRIS, a citizen of the United States, residing at Bremerton, in the county of Kitsap and 5 State of Washington, have invented certain new and useful Improvements in Automobile-Signals, of which the following is a specification.

This invention relates to direction indicating signals for motor vehicles. The object of my invention is the provision of inexpensively constructed and readily distinguishable devices of this character which are adapted to be attached to a vehicle for 10 the purpose of informing pedestrians or others, the intention of the driver to turn from the direction in which the vehicle is traveling.

The invention is illustrated in the accompanying drawings, in which—

Figure 1 is a fragmentary elevational view of the wind-shield structure of an automobile with signal devices embodying my invention associated therewith.

Fig. 2 is a rear elevational view of a portion of the arrow member of the apparatus, with the lower end of the casing shown in section.

Fig. 3 is a view of the parts represented in Fig. 2, shown partly in plan and partly in section, said section being taken through 3—3 of Fig. 2.

Fig. 4 is a perspective view of one of the arrow fluke elements.

Fig. 5 is a view similar to Fig. 1 with electrically actuated means for regulating the arrow member.

In said drawings, the reference numeral 10 designates a casing having an opening 40 at its outer side and is provided with clamping attachments 11 for securing it to one of the wind-shield posts 12 of an automobile.

A bell-crank lever, designated generally 45 by 13, is fulcrumed by means of a bolt 14 to the bifurcated lower end of said casing. One of the arms, 15, of said lever is substantially straight and the other arm, 16, is desirably curved and are respectively provided with longitudinal slots 15¹ and 16¹.

Engaging in the slot 16¹ is a finger 17 provided on an end of a rod 18 arranged for reciprocatory axial movements in a guide, such as 19, secured in the present instance to 50 the dash board 20 of the automobile.

21 represents a bar slidably connected by

means of apertured lugs 22 to the lever arm 15 for relative longitudinal movements, which are accomplished through the instrumentality of a rod 23 having one of its ends connected to the bar 21 at 24 and its other end to a bolt 25 secured to the casing below the lever fulcrum. 26 represent wing elements of an arrow whose stem or shaft is afforded by the bar 21. These wings are of 60 a substantially triangular shape to simulate when used supplementary to each other the head of a conventional arrow. Secured adjacent to the outer edge 27 of each wing and about the midlength of the same is the rear 65 end of a plate of substantially the form shown in Figs. 2 and 4, said plates each being provided with a portion 28 parallel with the outer edge 27 of the respective wing and having a forwardly and upwardly directed front portion 28¹ extending slightly beyond the inner edge 29 of the respective wing.

The forward ends of said plates are provided with apertures, such as 30, Fig. 4, to receive a pin 31 whereby the wings are pivotally connected to the outer end of the lever arm 15. At or about the bends between the portions 28 and 28¹ of the respective plates are provided apertures 32 to receive pins 33 for connecting the plates to the ends of links 34 whose other ends are connected to a stud 35 which extends through lever slot 15¹ and secured to the bar 21. By thus connecting the wings to the latter which is 70 movable longitudinally of the lever arm 15, and by controlling said bar by means of the connecting rod 23, as above explained, the wings are relatively distended when the lever arm 15 is in its horizontal full line position (Fig. 1), and are in relatively contracted relations when brought into their dotted line positions α (Fig. 1) by carrying the same with the lever arm 15 into the casing.

The apparatus as shown in Fig. 1 is manually actuated by means of a rod 18 located within convenient reach of the driver. In Fig. 5, however, I illustrate the invention in which the arrow is arranged to be displayed through electric power in opposition to the force of gravity tending to sheath the arrow within the casing. In the embodiment shown the bell-crank lever is fulcrumed to a bolt 14¹ secured to the casing 10¹ adjacent to the top end of the latter, and the rod 23 is connected to a bolt 25¹ disposed above such fulcrum. As shown in Fig. 5

the rod 18¹ whereby the lever is actuated, is in the nature of a core for solenoid 36 to afford an electromagnet for operating the signaling devices.

5 As shown, the circuit wires, *a*, *b* and battery B for supplying electric energy to the magnet and the branch connections *a*¹ and *b*¹ leading to an incandescent lamp 37 secured to one of the arrow wing elements for 10 illuminating the arrow in night driving are shown diagrammatically. The wires above referred to are normally in incomplete circuit, the same being closed by means of a switch 38 when the signal is to be employed.

15 The construction and operation of my improved automobile signal will be understood from the foregoing description.

What I claim, is—

1. In a signaling device for vehicles, the 20 combination with a casing adapted to be secured at a side of a vehicle, an arm, of a fulcrum support therefor connected to said casing, and means to swing said arm about said fulcrum support, a bar slidably connected to said arm for relative longitudinal movements, wings pivotally connected to said arm, links connecting said wings to said bar, means connecting said bar to the casing to effect the longitudinal movements of 25 the rod with respect to said arm whereby the wings are caused to collapse and distend with respect to each other as they are carried with said arm respectively into and from said casing.

30 2. In a signaling device for vehicles, the combination of a casing adapted to be secured at a side of a vehicle, a bell-crank lever fulcrumed therein, means connected with

one arm of said lever for effecting movements of the other arm into and from said 40 casing, a bar connected to the second named arm for movements longitudinally thereof, means connecting said bar with the casing for effecting its movements relative to the 45 second named arm when the latter is moved into or from said casing, a pair of wings connected pivotally to said second named arm, and operative connections between said wings and said bar whereby the wings are caused to be contracted or distended with 50 respect to each other as they are carried by the second named arm respectively into or from said casing.

3. In a signaling device for vehicles, the 55 combination of an arm, a fulcrum support therefor adapted to be secured at a side of a vehicle, means to effect the movements of said arm about said fulcrum to present the arm into substantially horizontal and vertical positions, a bar connected to said arm 60 for movements longitudinally of the latter, wing elements pivotally connected to said arm, links operatively connecting said wings to one end of said bar, and means connected to the bar and rendered operative by swinging of the arm about its fulcrum whereby said wings are collapsed and distended with respect to each other as the arm is respectively brought into its vertical and horizontal positions.

Signed at Bremerton, Washington, this 70
20th day of March 1920.

WILLIAM S. HARRIS.
